United States Patent Office

Des. 232,236

Patented July 30, 1974

232,236

MODULE FOR A FILTER MEDIA OR SIMILAR ARTICLE

Joseph N. La Borde, Baton Rouge, La., assignor to
Ethyl Corporation, Richmond, Va.

Filed Oct. 5, 1972, Ser. No. 295,135

Term of patent 14 years

Int. Cl. D23—01

U.S. Cl. D23—4

FIG. 1.

FIG. 2.

FIG. 3.

FIG. 4.

FIG. 1 is a perspective view of a filter media module embodying my new design,

FIG. 2 is a top plan view thereof,

FIG. 3 is a side view thereof, and

FIG. 4 is a cross sectional view taken on line 4—4 of FIG. 3.

I claim:

The ornamental design for a module for a filter media or similar article, substantially as shown.
